ELECTRIC LAMP HOLDER

Richard T. Kennedy, Oak Lawn, and James L. Hvale,
Chicago, Ill., assignors to Bell Electric Company,
Chicago, Ill.

Filed Oct. 29, 1973, Ser. No. 410,738

Term of patent 14 years

Int. Cl. D26—03

U.S. Cl. D48—20 K

FIG. 1

FIG. 2

FIG. 3

FIG. 4

FIG. 6

FIG. 7

FIG. 5

FIG. 1 is a perspective view of an electric lamp holder showing our new design;

FIG. 2 is a top view thereof;

FIG. 3 is a side elevational view thereof;

FIG. 4 is a bottom view thereof;

FIG. 5 is an elevational view of the side opposite the side shown in FIG. 3;

FIG. 6 is a front elevational view thereof; and

FIG. 7 is a rear elevational view thereof.

The holder is shaded to indicate contrast. The stand is broken away to indicate indeterminate length.

We claim:

The ornamental design for an electric lamp holder, substantially as shown and described.
